(57) **CLAIM**

The ornamental design for a retro full-grille front fascia, substantially as shown and described.

DESCRIPTION

FIG. 1 is a perspective view of a retro full-grille front fascia showing the new design, it being understood the vehicle shown fitting the bumper is for illustrative purposes only and forms no part of the claimed design;

FIG. 2 is a front view thereof;

FIG. 3 is a top view thereof;

FIG. 4 is a bottom view thereof;

FIG. 5 is a rear view thereof;

FIG. 6 is a left side view thereof; and,

FIG. 7 is a right side view.
